INTERMITTENT FEELER MECHANISM FOR LOOMS

Application filed March 29, 1930. Serial No. 439,942.

This invention relates to feeler mechanisms for looms and is more particularly directed to feeler mechanisms of the intermittent type wherein the feeler has periods of activity and 5 periods of inactivity during weaving with the same supply of filling in the shuttle.

As now ordinarily constructed, intermittent feeler mechanisms comprise a feeler which is normally under the influence of a 10 spring tending to move the feeler to feeling position to feel for the filling during its periods of activity, and a latch or detent is usually employed for holding the feeler in a 15 frontward position against the stress of the feeler spring during its periods of inactivity, and means have been employed for freeing the feeler from the latch or detent at intervals that the feeler may move under the normally acting stress of the spring to its rearward 20 feeling position.

In accordance with the present invention the stress of the feeler spring is so controlled that during the inactive periods of the feeler the spring is entirely relieved from exerting 25 any stress or action upon the feeler and periodically the feeler is moved to its feeling position to impart stress to the spring during the beat-up, and should the feeler detect a working supply of filling in the shuttle the 30 spring is again released so that the feeler may rest idly in any front position to which it may be moved quite free from spring control.

The object and purpose of the present invention is to provide a feeler mechanism of 35 the above indicated type and operation wherein the mechanical means employed may be simplified and the feeler caused to act intermittently to detect the condition of the filling in the shuttle.

40 The invention and novel features thereof will best be made clear from the following description and the accompanying drawings of one good practical form thereof.

In the drawings:

45 Fig. 1 is a perspective view showing portions of a loom having the present invention applied thereto;

Fig. 2 is an enlarged side sectional elevation of the feeler mechanism showing the 50 latter in its normal inactive position;

Fig. 3 is a similar view showing the feeler and the relation of parts when it is in active position;

Fig. 4 is an enlarged detail in perspective showing the relation of parts when the feeler 55 detects a working supply of filling in the shuttle less than that contained on a full bobbin, but wherein the filling is not yet substantially exhausted; and

Fig. 5 is a view similar to that of Fig. 4 60 showing the relation of parts when the shuttle detects substantial exhaustion of filling in the shuttle.

Feeler mechanisms are now ordinarily employed for effecting replenishment of filling 65 when that in the active shuttle has become substantially exhausted, but since the details of the replenishing mechanism form no essential parts of the present invention and are now well understood in the art, their illustration and description are not deemed necessary. 70

The loom frame has extending therefrom, as usual, the shipper stand 1 from which projects a portion 2 for the support of the feeler stand, which may be clamped thereto in any usual manner. In the present instance the feeler stand has the upright member 4 thereof provided with an opening 5 through which extends a bolt 6 passing through an 80 elongated slot 7 in the projecting portion 2 of the loom frame. The upper portion of the feeler stand, in the present instance, comprises an arm 8 through which extends a securing bolt 9 threaded into a boss or support 75 85 10 constituting the feeler stand proper. The support 10 has an opening therein through which extends a hollow fixed member 11 which may be clamped in place by the bolt 9.

Within the hollow member 11 the feeler and certain operative parts are mounted. As shown, the feeler consists of a slide 12 which fits the hollow member 11 and to the rear end portion of the slide 12 the feeler 13 is pivotally connected, as at 14, so that the feeler 95 may move longitudinally of the shuttle when on a detecting beat the feeler detects substantial exhaustion of filling.

The feeler 13 has its rear end portion provided with teeth 15 which may act as usual 100

to hold the feeler from side slipping movement when it detects a working supply of filling in the shuttle, and between the toothed portion 15 and the pivotal support 14 of the feeler is connected a transmitter 16, the end portion of which is connected at 17 to a pivoted member 18 carried on the end of an actuator 19. The pivoted member has a lateral projection 20 which is normally out of the path of movement of an operating member 21 (Fig. 1) which may be a part connected to the usual cam follower. The actuator 19 is itself pivotally connected at 22 to the arm 23 rising from the usual transverse or rock shaft 24 mounted on the breast beam of the loom and associated at its opposite end with the filling replenishing mechanism, the construction being such that should the actuator 19 be moved frontwardly, the transverse or rock shaft 24 will be rocked and set in operation a train of mechanism for effecting replenishment of filling when the shuttle returns to the replenishing side of the loom. The train of mechanism thus far described may be of any usual construction as now well understood in the art.

The feeler portion 12 has connected to it a feeler stem 25 which extends frontwardly through the hollow member 11 and mounted for sliding movement on the front portion of the feeler stem is the sleeve 26. Interposed between the portion 12 of the feeler and the sliding sleeve 26 is the feeler spring 27, the construction being such that should the sleeve 26 be moved rearwardly on the feeler stem it will act through the spring 27 to move the feeler into rearward feeling position so that on detecting beats the spring will be stressed to return the feeler to feeling position under circumstances which will later appear.

Extending from the support or boss 10 is an arm 28 which constitutes a fixed support, and pivotally mounted on the fixed support 28 at 29 is an arm 30, the upwardly extending portion of which is frontward of the sleeve 26, which may be conveniently provided with an enlarged head portion 31 against which the upper end of the arm 30 may act.

As hereinbefore stated, the feeler stem has the sleeve 26 which constitutes a spring controller, slidably mounted thereon, and the stem of the feeler extends through the sleeve and is provided at its front portion with an enlargement 32 which may be conveniently secured thereto by threading the enlargement 32 upon the feeler stem.

From the construction thus far described it will be apparent that should the arm 30 be swung about its pivotal support 29 in a contra-clockwise direction, viewing the drawings, it will move the spring controller or sleeve 26 rearwardly and as it acts upon the spring 27 it will correspondingly move the feeler into its rearward feeling position, and

if the controller 26 is maintained in its rearward position as stated, the feeler will be placed under the stress of the spring on a detecting beat as the feeler feels for the filling in the shuttle. Should a working supply of filling be present in the shuttle the toothed end portion of the feeler will prevent side slipping movement by engagement with the filling.

The arm 30 has connected thereto a projecting portion 33 the end of which rests upon a pin 34 under the stress of a light spring 35, one end of which is connected to the projection 33, as shown, and the other to a pin 36 mounted on the horizontal extension 37 of the feeler stand.

The pin 34 is mounted for sliding movement in a casing 38 which may be conveniently mounted on the horizontal extension 37 of the feeler stand, and cooperating with the pin 34 is the wire 39 surrounded by a flexible metallic sheath 40.

Mounted on the loom frame, as indicated in Fig. 1, is a bracket 41 having a tubular support 42 for a pin 43 which is slidable in the support, and the flexible wire 39 covered by its sheath 40 rests against the inner end of the pin, with the result that should the pin 43 be moved lengthwise in its bearings it will act upon the flexible wire 39 and cause an upward movement of the pin 34 hereinbefore described.

In accordance with the present invention, the feeler has periods of activity and periods of inactivity and means are employed for periodically moving the flexible wire 39 lengthwise to initiate a period of activity of the feeler.

In the present instance of the invention, the pin 43 is given its sliding movement in its bearing 42 through the take-up mechanism, although it will be apparent that any going part of the loom may be utilized for this purpose, which will act periodically to move the pin 43 and perforce the flexible wire 39, to effect movement of the arm 30 as indicated.

In the present instance of the invention, the bracket 41, Fig. 1, has pivotally mounted thereon at 44 an arm 45 against which the free end of the pin 43 rests, and the arm 45 has a cam surface 46 adapted to be engaged by a lug 47 mounted on the gear wheel 48 constituting one member of the take-up, with the result that when the projection 47 rides along the cam portion 46 of the lever 45, the flexible wire 39 will be moved lengthwise to thereby act upon the arm 30 and move it contraclockwise about its pivotal support.

Pivotedly mounted on the fixed support 28 at 49 is a locking lever 50 provided with a locking shoulder 51 adapted to engage in front of the sleeve 26, or the enlargement 31 thereof, when the sleeve or spring controller has been moved rearwardly to place the feeler in feeling position.

5. The locking lever 50 is normally under the influence of a spring 52 tending to swing it upwardly, one end of this spring 52 being secured to the fixed support at 53 and the other to the hooked end portion 54 of the locking lever.

10. The front end portion of the locking lever 50 is provided with a bevel or incline 55 which is adapted to be engaged by the front end portion of the feeler stem when the feeler is moved frontwardly on a detecting beat by a working supply of filling in the shuttle, and thereby trip the locking lever and free the feeler and spring controller to frontward movement as the feeler moves frontward under the impact of a full bobbin on a detecting beat. The front end portion of the feeler stem, as 32, will thereafter rest upon the upper surface 56 in frictional engagement therewith and consequently prevent the loom vibration from disturbing the position of the parts with the feeler in its frontward inactive position.

15. From the construction described it will be apparent that the feeler has periods of activity and periods of inactivity during weaving with the same supply of filling in the shuttle, and during its periods of activity the spring controller and consequently the feeler 20 will be held in rearward position as indicated in Fig. 1.

25. As the filling is withdrawn from the shuttle and its diameter consequently becomes less in front of the feeler, the feeler will be moved frontwardly a less distance than when a full bobbin is present in the shuttle, with the result that the feeler stem will engage the incline 55 of the lever 50, trip the spring controller or sleeve 26, which will then take an 30 intermediate position with respect to the trip lever 50, as indicated in Fig. 4. With the parts as indicated in Fig. 4 and the filling 35 partially exhausted it is desirable that the feeler and the feeler controller or sleeve 26 be prevented from displacement by the loom vibration, and to this end the trip lever 50 is provided with a surface 57 between the shoulder 51 and the incline 55 which will bear upon the enlargement 31 of the sleeve, the 40 feeler then being in its inactive position and frictionally held. On the initiation of the next period of activity of the feeler it will be again moved rearwardly into feeling position by the arm 30, as indicated in Fig. 5, and 45 will be held in such position by engagement with the locking shoulder 51 of the trip lever 50, and should substantial exhaustion of filling be indicated the feeler will side slip, as indicated in Fig. 5, and initiate filling 50 replenishment.

55. On the following detecting beat with a full bobbin in the shuttle the feeler will be moved frontwardly the full distance prescribed by the diameter of the filling and cause the feeler 60 stem to act upon the incline 55 of the trip

lever, thereby freeing the feeler and the sleeve 26 to frontward movement into idle position, as indicated in Fig. 2, where the parts will remain until the next period of activity of the feeler.

70. With a full supply of filling in the shuttle, the feeler and feeler controller or sleeve 26, will rest in a frontward or idle position, as indicated in Fig. 2, and upon actuation of the arm 30 to initiate an active period of the 75 feeler, the controller 26 and perchance the feeler will be moved rearwardly, as indicated in Fig. 3, and be locked in this position by the shoulder 51 as the lever 30 returns to its initial position, as indicated in Fig. 1. Should the 80 feeler at this time detect a working supply of filling in the shuttle it will be moved frontwardly and by engagement of the front end portion of the feeler stem with the incline of the trip lever will trip the lever to free the 85 spring controller 26 and permit the feeler and spring 27 to be moved frontwardly on the detecting beat.

Should the feeler detect an approach to substantial exhaustion of filling, the parts will be 90 positioned as indicated in Fig. 4 and frictionally held from disturbance by loom vibration. On the next period of activity the feeler will be moved rearwardly again by the arm 30 acting through the spring controller or sleeve 26 and 95 upon detection of substantial exhaustion of filling the feeler will side slip and effect replenishment of filling.

100. The lay 58 may be of usual construction and be provided with the detecting shuttle box 59, the front wall 60 of which has an opening 61 which registers with an opening 62 in the shuttle 63 when the shuttle is properly boxed, to thereby permit the feeler to enter the shuttle, as usual, and detect the condition of filling 105 therein.

What is claimed is:

1. In a feeler mechanism for looms, the combination of a feeler stand, a feeler mounted on the feeler stand for movement towards and from the front of the loom and having a frontwardly extending stem, a feeler spring, a spring controller constituted as a sleeve mounted on the feeler stem for placing the feeler under rearward stress of the spring for periods of activity of the feeler, a locking lever having a locking shoulder for engaging and holding the sleeve in its spring stressing position, and means constituted as an incline on the locking lever frontward of the locking shoulder adapted to be engaged by the front end portion of the feeler stem for tripping the lock when the feeler is moved frontwardly by a working supply of filling in the shuttle on a detecting beat that the feeler may remain at rest in front position during periods of feeler inactivity.

110. 2. In an intermittent feeler mechanism for looms, the combination of a feeler stand, a 115

fixed tubular member fixed thereto, a feeler mounted on the stand for movement towards and from the front of the loom and having a frontwardly extending stem, a feeler spring mounted on the feeler stem and enclosed by the tubular member, a spring controller constituted as a sleeve mounted for sliding movement on the feeler stem and into said tubular member, means actuated by a going part of the loom for moving the spring controller sleeve periodically into the tubular member to place the feeler spring under stress that the feeler may be moved to rearward feeling position, a locking lever having a locking shoulder forward of the tubular member for engaging the sleeve to hold the sleeve in its rearward position, and a trip portion forward of the locking shoulder for engagement by the end of the feeler stem when it is moved frontwardly by a full bobbin for tripping the lock that the feeler and sleeve may be moved frontwardly into idle position and the stress of the feeler spring be relieved.

3. In an intermittent feeler mechanism for looms, the combination of a feeler stand, a feeler mounted on the feeler stand for movement towards and from the front of the loom and having a feeler stem, a feeler spring, a spring controller sleeve mounted for sliding movement on the feeler stem, means actuated periodically from a going part of the loom for moving the sleeve rearwardly and the feeler to rearward feeling position under the action of the feeler spring, a locking lever having a locking shoulder for holding the sleeve in its rearward position, and a projection in front of the locking shoulder adapted for engagement by the front end of the feeler stem to free the sleeve from the locking shoulder when the feeler is moved frontwardly by a working supply of filling on a detecting beat that the feeler may rest in idle position freed from the stress of the feeler spring.

4. In an intermittent feeler mechanism for looms the combination of a feeler mounted for movement towards and from the front of the loom, a feeler spring which exerts a rearward stress upon the feeler during its periods of activity and exerts no stress upon the feeler during its periods of inactivity that the feeler may freely rest in any frontward position to which it is moved, a spring controller constituted as a sleeve slidably mounted on the feeler and periodically actuated to move the feeler to feeling position, a latch for holding the sleeve in its rearward position until the feeler is moved frontwardly by a working supply of filling on a detecting beat and thereupon freeing the feeler that it may float at rest during periods of inactivity, and means for preventing accidental movement of the sleeve under the loom vibration while the feeler is in idle position.

5. In an intermittent feeler mechanism for looms the combination of a feeler mounted

for movement towards and from the front of the loom, a feeler spring which exerts a rearward stress upon the feeler during its periods of activity and exerts no stress upon the feeler during its periods of inactivity that the feeler may freely rest in any frontward position to which it is moved, a spring controller constituted as a sleeve slidably mounted on the feeler and periodically actuated to move the feeler to feeling position, a latch constituted as a lever having a locking shoulder for engagement with the sleeve for holding the sleeve until the feeler is moved frontwardly by a working supply of filling in the shuttle, and a friction surface carried by the latch for engagement by the sleeve to prevent displacement of the feeler by the loom vibration when the feeler is moved frontwardly by less than a full bobbin.

6. In an intermittent feeler mechanism for looms, the combination of a feeler, a feeler spring which exerts a rearward stress upon the feeler during its periods of activity and exerts no stress upon the feeler during its periods of inactivity that the feeler may rest freely in any front position, a spring controller formed as a sleeve mounted on the feeler and periodically active to move the feeler to feeling position and place the spring under stress against the feeler on a detecting beat, a latch constituted as a pivoted lever having a locking shoulder for engagement with the spring controller and an inclined front end portion for engagement by the front end of the feeler when it is moved frontwardly by a working supply of filling on a detecting beat to thereby depress the latch and free the controller.

7. In an intermittent feeler mechanism for looms, the combination of a feeler, a feeler spring which exerts a rearward stress upon the feeler during its periods of activity and exerts no stress upon the feeler during its periods of inactivity that the feeler may rest freely in any front position, a spring controller formed as a sleeve mounted on the feeler and periodically active to move the feeler to feeling position and place the spring under stress against the feeler on a detecting beat, a latch constituted as a pivoted lever having a locking shoulder for engagement with the spring controller and an inclined front end portion for engagement with the front end of the feeler when it is moved frontwardly by a working supply of filling on a detecting beat to thereby depress the latch and free the controller, and a friction surface carried by the latch between the locking shoulder and inclined front end to engage the sleeve when the feeler is moved frontwardly by less than a full bobbin.

In testimony whereof, I have signed my name to this specification.

ELVIN D. MACARTHUR.
